UNITED STATES PATENT OFFICE.

H. CLAY BASCOM AND CYRUS A. HODGES, OF TROY, NEW YORK, ASSIGNEES
TO SAID BASCOM.

DESIGN FOR A HEATING-STOVE.

SPECIFICATION forming part of Design No. 15,386, dated September 9, 1884.

Application filed June 17, 1884. Term of patent 7 years.

To all whom it may concern:

Be it known that we, H. CLAY BASCOM and CYRUS A. HODGES, citizens of the United States, residing in the city of Troy, in the county of Rensselaer and State of New York, have jointly invented and produced a new and original Design for Heating-Stoves, of which the following is specification, reference being had to the accompanying cut, print, or engraving of a stove having said design.

This design embraces new and distinct parts and combinations of parts, which go to make up the whole design, as shown in the aforesaid print and hereinafter specified.

15 One general distinguishing feature of this design is the shape and ornamentation of the main portion, consisting of the top A, sections B and C, and the parts D, E, and F, as shown.

20 The design for the top A consists of the plane outer rim, b, convexly-curved inner border, a, having the series of ornaments a', and the flat top surface, p.

25 Another feature is the configuration and ornamentation of the portion consisting of the downwardly-flaring concavely-curved part e, having along its lower edge the series of semi-rosettes e', the downwardly-flaring part f, and the projecting rim r, having the series of semi-rosette ornaments, as shown.

30 The design for the feed-door G consists of the outer border-molding, s, and the convexly-curved surface s', having the central rosette, t, with the scroll vine ornaments t', and the scroll leaf ornaments t'.

35 The design for the base-top D consists of the quadrilateral plane inclined border j, having rounded corners, the flat top surface, k, having the scroll vine ornaments u, and the 40 concavely-curved circular ring l, having the draft-apertures l'.

45 The design for the upright quadrilateral base portion E consists of the rounded corners m', between the oblong quadrilateral panels m, having the border-molding m', and the compound ornamentation consisting of the middle ornament, v, outer scroll leaf ornaments, v', and the intermediate ornaments v'.

50 The design for the quadrilateral round-cornered bottom plate, F, consists of the outer plane inclined border, o, the flat top part, o',

and the intervening convexly-curved border n, having the corner ornaments, n', and the side rows of angular ornaments w, and quarter-rosettes w'.

55 The design for the legs consists of the convexly and concavely curved surface x, having therein the compound rosette y, the upper and lower beadings, z z', and the foot z'.

The whole design embraces the shape and 60 ornamentation of the top A, section B, consisting of the parts c and d, section C, consisting of the parts e f r g h i i', parts D, E, and F, door G, and the legs.

We claim as new—

1. In a design for a stove, the shape and ornamentation of the portion consisting of the parts A B C D E F, as set forth.

2. In a design for a stove, the shape and ornamentation of the top A, consisting of the 70 parts a a' b p, as shown and described.

3. In a design for a stove, the configuration and ornamentation of the portion consisting of the parts c, c', f, and r, as shown and described.

4. In a design for a stove, the shape and 75 ornamentation of the door G, consisting of the parts s s' t t' r, as set forth.

5. In a design for a stove, the shape and ornamentation of the base-top D, consisting of the parts j k u l l', as shown and described. 80

6. In a design for a stove, the shape and ornamentation of the upright base portion E, consisting of the parts m m' m' r v' v', as shown and described.

7. In a design for a stove, the shape and 85 ornamentation of the bottom plate, F, consisting of the parts o o' n n' w w', as shown.

8. In a design for a stove, the configuration and ornamentation of the legs, consisting of the parts x y z z' z', as shown and described. 90

9. The design for a stove, consisting of the parts A B C D E F G and the legs, shaped and ornamented as set forth.

In testimony whereof we hereunto set our hands, in the presence of two subscribing witnesses, this 14th day of June, 1884.

H. CLAY BASCOM.
CYRUS A. HODGES.

Witnesses:
